(57) **CLAIM**

The ornamental design for a car body, as shown and described.

DESCRIPTION

FIG. 1 is a front elevational view of a car body showing my new design;

FIG. 2 is a rear elevational view thereof;

FIG. 3 is a left side elevational view thereof;

FIG. 4 is a right side elevational view thereof;

FIG. 5 is a top plan view thereof.

FIG. 6 is a front perspective view thereof; and,

FIG. 7 is a rear perspective view thereof.

The portions of the car body shown in broken lines form no part of the claimed design. The shading lines shown in the drawings represent the approximate three-dimensional contour of the design, and are not intended to indicate surface decoration.
